UNITED STATES PATENT OFFICE.

ALFRED WELLS CASE AND LAWRENCE W. CASE, OF HIGHLAND PARK,
CONNECTICUT.

APPARATUS FOR HEATING LIQUIDS.

SPECIFICATION forming part of Letters Patent No. 621,081, dated March 14, 1899.

Application filed January 27, 1898. Serial No. 668,234. (No model.)

To all whom it may concern:

Be it known that we, ALFRED WELLS CASE and LAWRENCE W. CASE, citizens of the United States, and residents of Highland Park, county of Hartford, and State of Connecticut, have invented certain new and useful Improvements in Apparatus for Heating Liquids, of which the following is a full, clear, and exact description, whereby any one skilled in the art can make and use the same.

The object of our invention is to provide an apparatus by means of which liquids and more particularly water may be subjected to a temperature equal to that of the boiling-point, so as to destroy all germs, and to employ in such process and apparatus means which enable the work to be done with the smallest possible expenditure of heat and without loss of heat in the process, and this automatically.

To this end our invention consists in the combination of means to the stated end, as hereinafter described, and more particularly recited in the claims.

Referring to the drawings, Figure 1 is a view of our improved apparatus with parts cut away in section to illustrate the construction. Fig. 2 is a plan view of our improved apparatus. Fig. 3 is a detail view of a modified form 30 of device for applying additional heat.

In the accompanying drawings the letter *a* denotes a supply-pipe through which water flows under sufficient pressure into the apparatus to cause it to rise through the heat-transferrer *b* into the heating-chamber *c*.

The heat-transferrer *b* comprises an outer casing *d*, an inner cylinder *e*, between the walls of which a space is formed within which the closely-fitting coil *f* of the supply-pipe is located. The purpose of the inner cylinder *e* is simply to form one wall of the pipe-space, and the pipe is of such diameter that the coils extend across and fill the space laterally, making contact with the inner surface of the wall *d* and the outer surface of the cylinder *e*, thus leaving a spiral pathway *g* about the coil and between it and the adjacent walls within the greater part of the length of the heat-transferrer. The object of this construction is to cause inflowing water to pass through the transferrer in coils and in continuous contact

with the walls of the supply-pipe, so that the heat in the outgoing water may be transferred by conduction to the inflowing water, and thus cause the latter to be delivered into the heating-chamber *c* at a temperature nearly equal to that at which water flows out from the chamber *c*. The inner cylinder *e* is supported within the coils of the supply-pipe in the transferrer *b* in any convenient manner. After passing through this heat-transferrer *b* the supply-pipe *a* delivers into the bottom of the heating-chamber through a valve *h*. In the form described the heat-transferrer *b* is arranged in an upright position, and the heating-chamber *c* is placed above it. Within the heating-chamber *c* is a regulator-valve *i*, which in the form shown consists of a hollow vessel open at the top and located within guide-supports, which serve to maintain it in an upright and central position in the chamber.

The guide-supports in the form shown consist of the coil *k'* of the steam-pipe *k*, this coil being arranged within the chamber *c* near its outer wall. A discharge-pipe *l* extends from a point where its open end is located within the regulator-valve *i* out through the mouth of the latter and through the wall of the heating-chamber to the cover of the heat-transferrer *b* through a hole in which it enters, so that water may flow through this pipe *l* from the heating-chamber *c* into the transferrer *b*.

The water within the heating-chamber *c* is raised to the boiling-point as by means of steam flowing into the coil *k'* and the delivery of hot water into the chamber *c* from the end of the coil which opens into the chamber *c*. A factor in raising the water in this heating-chamber is the steam flowing through the pipe *k*, and the rate of flow of the steam and water of condensation is regulated by the valve *k*², located in the pipe at a point outside of the wall of the chamber and between the coil and the point *k*³, where the hot water of condensation is discharged into the water near the bottom of the heating-chamber *c*. Instead of discharging into the chamber the pipe at the end of the coil may be connected with any desired storage vessel for distilled water.

The water after having been discharged into the heat-transferrer *b* through the pipe

l flows in a spiral path around and in close contact with the coils of the supply-pipe and by conduction transfers its heat to the inflowing water. The water reaching the bottom 5 of the shell of the transfferer goes through the pipe *l'* and discharges at *l*² into a reservoir *o*, this reservoir having a discharge-pipe *p*, provided with a valve *p'*, which controls the outflow of purified water. Within this reservoir 10 is a float *q*, which is connected, as by means of a lever *r*, with the valve *k*². The float may also be connected by suitable mechanism with means for controlling the flame *m*, (when this 15 form of heating device is used in place of the steam-coil,) so that the position of the float will control the degree of extra heat supplied to the heating-chamber.

The pipe *l'* bends at a point above the level 20 of the heating-chamber, so as to prevent the siphoning over of water through the discharge-pipe *l* after the flow begins. The height of this bend in the pipe *l'* above the level of the heating-chamber determines the 25 degree of back pressure of the column of water upon the outflowing stream from the heating-chamber. The boiling-point of water varies with the degree of pressure upon its surface, and by regulating this pressure the comparative temperature of the outflowing water 30 may be controlled. The greater the back pressure the greater the heat applied and carried off. To prevent the apparatus from becoming air-bound, the heating-chamber is provided with an air-valve *c*¹ and the pipe *l'* 35 with a similar valve *c*² at the highest point of the bend.

The supply-pipe *a* is provided with a suitable filter *a'* and the discharge-pipe *l'* with a suitable filter *a*² in order to remove from the 40 water impurities held in mechanical suspension.

The operation of the device is as follows: The several parts of the apparatus being arranged in the relative positions shown, water 45 is allowed to flow into the heating-chamber and fill the system. Heat is then applied through the coil *k* (or the flame *m*) until the water begins to flow through the discharge-pipe *l*, the transfferer *b*, and the pipe *l'* into 50 the reservoir *o*. The rate of flow is determined by the position of the regulator-valve *i*, which in its lowermost position closes the opening at the valve *h*, so as to prevent the inflow of water, but when lifted therefrom, as 55 by the buoyancy of the vessel due to the discharge of water therefrom, again opens the valve for the water to flow into the chamber. If the discharge has been too rapid, it is controlled by the position of the float *q* in the 60 reservoir *o*, the raising of the water-level in the reservoir shutting the valve *k*² or turning down the flame *m*.

The regulator-valve, as stated, is a hollow vessel open at the top in order to permit water to flow into it over its upper edge and when filled sinking, so as to close the valve *h*; but when the discharge of water from the

body of the hollow vessel increases its buoyancy it rises, so as to open the valve *h* and permit a further flow of water into the heating-chamber. The movements of this regulator-valve are gradual and not abrupt, and while the device is in operation for heating water the valve *h* is open to a degree for a greater part of the time. The rising-and-falling movements and the opening and closing of the valve *h* are automatic, and by the described method a practically continued flowing of water through the apparatus is obtained.

The apparatus is maintained in working condition and in operation by the very slight expenditure of heat applied to the heating-chamber, this extra heat imparted to the water within the heating-chamber being practically wholly saved by its transference to the inflowing supply of cold water to the system.

In the within-described apparatus a feature of our invention is that additional heat is applied to all of the liquid treated in the heating-chamber, and a further feature and advantage are that the liquid passes in at the bottom, where the temperature is the lowest, and flows over the upper edge of the hollow valve-body, where the temperature is the highest, 95 and into this hollow body of the valve before discharging, so that none of the liquid can pass out without having been subjected to the highest temperature within the heating-chamber. This insures a thorough heating of the 100 liquid to such degree as may be necessary to the treatment of a liquid, as water, for sanitary purposes.

We claim as our invention—

1. In combination in an apparatus for heating liquids, a heat-transferrer including an outer casing and an inner cylinder, passages for the flow of liquid toward and from the heating-chamber, one of said passages consisting of a coil closely fitting in a lateral direction the space between said casing and cylinder, and the other passage consisting of the space formed between the successive turns of said coil, a heating-chamber, and a regulator-valve located in the heating-chamber 115 whereby the flow of liquid therethrough is controlled by the changes of temperature in the chamber, all substantially as described.

2. In a liquid-heating apparatus in combination, a heat-transferrer comprising alternate contiguous passages located between the inner and outer walls of an annular chamber that form a portion of the walls of one of said passages, a heating-chamber, tubular connections between the heating-chamber and the 125 channels in the transfferer, a current-regulator located within the heating-chamber, means for imparting added heat to the contents of the heating-chamber, a reservoir and means depending on the level of the water in 130 the reservoir for controlling the degree of additional heat applied to the heating-chamber, all substantially as described.

3. In combination in an apparatus for heat-

ing liquids, a heat-transferrer having alternate contiguous passages for the flow of liquid toward and from a heating-chamber, a heating-chamber, a regulator-valve in said chamber with a body open at its top, a discharge-pipe extending into the valve-body, a reservoir, a float located in the reservoir and means connecting said float with a device for controlling the heat-supply to the heating-chamber, all substantially as described.

4. In combination in an apparatus for heating liquids, a heat-transferrer including an outer casing and an inner cylinder with an annular space therebetween, inlet and outlet passages for the flow of liquid toward and from a heating-chamber, one of said passages consisting of a coil closely fitting in a lateral direction the annular space between said casing and cylinder and the opposite passage being formed between the successive turns in said coil, a heating-chamber located above the heat-transferrer, means for imparting additional heat to all the liquid entering the heating-chamber, and means for regulating

the flow of liquid through said chamber, all 25 substantially as described.

5. In combination in an apparatus for heating liquids, a heat-transferrer having separate contiguous passages for the flow of liquid toward and from a heating-chamber, a heating-chamber located above the heat-transferrer, means for imparting additional heat to all the liquid entering the heating-chamber, means for regulating the flow of liquid through the said chamber, a discharge-pipe 35 extending from the heating-chamber to the transferrer and a discharge-pipe extending from the transferrer to a reservoir and having a bend in said discharge-pipe located at a level above the highest point of the discharge-pipe which extends from the heating-chamber to the transferrer, all substantially as described.
